UNITED STATES PATENT OFFICE.

BIRNEY DYSART, OF CINCINNATI, OHIO.

ADDING AND RECORDING MACHINE.

1,278,612.

Specification of Letters Patent. Patented Sept. 10, 1918.

Application filed May 25, 1917. Serial No. 170,864.

To all whom it may concern:

Be it known that I, BIRNEY DYSART, a citizen of the United States, residing at the city of Cincinnati, county of Hamilton, and State of Ohio, have invented a new and useful Adding and Recording Machine, of which the following is a specification.

This invention relates to adding and recording machines.

10 Some of the adding and recording machines now on the market are equipped with a limited number of special types or logotypes, but the number thereof which can be used on any particular machine is so limited that their extent of use for making out statements and performing other classes of similar work is greatly restricted.

I am aware that separate typewriting or recording means have been used in cooperation with the regular printing or listing mechanisms of adding machines, so that a comparatively wide range of words and characters may be printed in any desired relation to the amounts and the totals there-
25 of as listed by the recording mechanism of the adding machine; but I know of no adding machine whose regular recording instrumentalities under control of the differential mechanism are capable of producing more than a very limited number of words or characters, the number thereof being usually determined by the number of special types or logotypes which can be carried by a single type-carrier at one time.

30 Since it is essential that the type bars or type blocks, on which the logotypes or special characters are engraved, shall be securely retained in their supports on the type-carriers of an adding machine, as these machines are now constructed only those words or special characters can be printed for which provision has been made in the assembling of the machine during the manufacture thereof. It is a consequence of this condition that the removal of one set of logotypes and the substitution of others in place thereof requires the services of a skilled mechanic provided with the necessary tools.

35 My present invention relates to the printing mechanism of the machine, and it has particular reference to that class of adding and recording machines which includes a series of type-carriers operable side by side under control of differential mechanism to

record items or amounts set up in the differential mechanism, and to operate the transfer mechanism for causing the adding mechanism of the machine to add the items or amounts listed.

An object of my present invention is to make provision for the equipment of machines of the class mentioned with an unlimited number of words and special characters, which may be varied or changed at will, such equipment including a series of type bars or type blocks for printing such words or abbreviations as it may be desired to print in connection with the work performed by the listing mechanism of the adding machine, and means for removably supporting said type-bars or type blocks upon one of the type-carriers under control of the differential mechanism of the adding machine. By provision of such equipment the proper word or abbreviation will be automatically listed or printed in alignment with the printed items or amounts listed by the adding machine and at the same operation.

In the attainment of the foregoing object, I have provided means whereby the special types of logotypes mounted on the type-carriers of the adding machine may be easily and quickly removed from their supports and any others desired substituted by an ordinary operator of the machine without the services of a skilled mechanic and without the necessity of tools of any kind. In this way I make it possible to print any number of words or special characters by the ordinary recording mechanism of an adding machine, the number of such words or special characters being limited only by the number of logotypes or special types that are available.

For convenience I have illustrated my invention embodied in a Dalton adding machine, though it will be understood that its use and capability is not limited to that specific machine.

In the accompanying drawings, wherein the invention is illustrated,

Figure 1 is a view of the differential and recording mechanism of a Dalton adding machine having my invention applied therein.

Fig. 2 is a front elevation of portions of the type-carriers with one of which my present invention is combined.

Fig. 3 is an illustration of one of the type-

carriers of the machine having my invention combined therewith, the type case being in section.

Fig. 4 is a sectional view of the type-carrier illustrated in Fig. 3, approximately on the line 4—4 thereof.

Fig. 5 is a sectional view on the line 5—5 of Fig. 4.

Fig. 6 is an enlarged front view of a portion of the type-carrier with which my invention is combined.

Fig. 7 is a sectional view of the type-carrier illustrating a modification of the invention.

Fig. 8 is a sectional view of the type-carrier illustrating a modified form of retaining device for the type-blocks.

Fig. 9 is a perspective view of the modified form of retaining device detached from the type-carrier.

Fig. 10 illustrates a specimen of the work performed by the machine having my invention embodied therein.

The Dalton adding machine in which I have illustrated my present invention is manufactured in substantial conformity with the disclosures of Hubert Hopkins Patent No. 1,039,130, dated September 24, 1912. The machine of said patent comprises a series of ten numeral key levers 1 having their operating keys 2 arranged in convenient manner in a key board. The key levers are operable to set the stops 3 of the differential mechanism to represent the digits of the numbers or amounts to be recorded and added by the machine. Said machine also includes a series of type-carriers 4 suspended from a shaft 5 and actuated in one direction by springs 6, as required to position said type-carriers for recording the numbers or amounts set up in the differential mechanism. The type-carriers are returned to their idle positions or starting points by a rod or bail 7 supported transversely in front of the vertical portions of the type-carriers by swinging arms 8 also supported by the shaft 5 from which the type-carriers are suspended. After each amount or number has been recorded the type-carriers are restored to their starting points by the rod or ball 7. Each type-carrier is co-operatively related with the rack 9. The racks 9 are also suspended from the shaft 5 and co-operate with the differential stops 3 to limit movement of the type-carriers and to stop them side by side to position the printing type in alignment for the purpose of printing or listing the items or amounts set up in the differential mechanism. The racks 9 also operate the adding pinions 10 in adding and transferring operations in the well understood manner, as described in said Hubert Hopkins patent and as exemplified in the commercial Dalton adding machine,

Each type-carrier supports a series of movable type blocks 11 which are selectively positioned side by side adjacent to the platen 12 under control of the differential mechanism to record the numbers set up in the differential mechanism. After the type-carriers have stopped, the type driving hammers 13 operate to drive the aligned type to list or print upon the paper operating around the platen.

By my present invention certain of the type-carriers are equipped with means for selectively mounting thereon and removing therefrom special type blocks for printing special characters, or words, or abbreviations thereof in alignment with the numbers or amounts listed by the type 11. The special type-carriers, in the illustrated embodiment of the invention, are also under control of the differential mechanism, so that at the same operation at which any number or amount set up in the differential mechanism is printed, a proper identifying character, word or abbreviation may be printed in alignment therewith, such for instance as a date, or the abbreviations Dr., Cr., Bal., Com., Dis., and various other commercial words or abbreviations. Although I have illustrated only one of the type-carriers thus equipped, it is readily apparent that others may be similarly equipped if desired. While the logotype-carrier illustrated is under control of the differential mechanism, it is clear that it may be otherwise controlled, and the invention is not limited to control by the differential of the adding machine.

The type-carrier with which I have illustrated my present invention is the one in the highest numerical order and is at the extreme left relative to the operator facing the machine. This type-carrier is preferably spaced from the adjacent type-carrier in the next lower numerical order and has affixed thereto a type supporting case 14. The side edges of the case 14 are turned toward and bear against the type-carrier. The side walls of the case thus arranged are provided with matching openings or slots in which the type blocks are mounted for longitudinal movement toward the platen when driven by the hammers 13 and away from the platen under control of the return levers. The case 14 is secured to the type-carrier by screws 15 passing through the case and engaging in threaded holes in the type-carrier and having the ends thereof counterpunched to prevent them from working loose, thus permanently securing the case to the type-carrier and preventing the screws from working loose.

The special type which I have provided are formed on the inner ends of the special type bars 16, said type bars having heads 17 contacting with the inner edge of the type-carrier and limiting outward movement

thereof. Said type bars are also formed with shoulders 18 on their outer ends adapted to contact with the type case 14 and limit inward movement of the type bars.

- 5 The mechanism for actuating the type bars outwardly after they are driven to print comprises a lever 19 pivotally supported on the type-carrier at the point 20 and engaging with shoulders on a number of 10 the type blocks; and a coöperating lever 21 pivotally supported on the type-carrier at the point 22 and engaging with shoulders on the remaining type blocks; said two levers having lateral extensions adjacent to 15 their pivots which are connected by a spring 23 by which said levers are actuated to return the type blocks to their normal positions after operation by the coöperating hammer.
- 20 The type blocks 16 are held in position by a retaining device which is substantially U-shaped in elevation and consisting of a wire bent to provide two arms 24 removably mounted between the type blocks 16 and the type-carrier supporting them and thus holding the types in position adjacent to the inner wall of the case 14, but leaving them loose and free for movement by the hammer coöperating therewith and by the 25 levers 19 and 21. The arms of the retaining device pass through openings in the upper end of the case 14 and contact with the side walls of the type case. Each of said arms is formed with a slight crimp or bend 25, said 30 crimps or bends being arranged to engage in the notches in which one of the type blocks operates, thus preventing the retaining device from being displaced in the operation of the machine but permitting it to be readily withdrawn by engagement with the upper portion 26 which connects the side arms thereof. The heads or shoulders 18 are of less thickness or width than the depth of the notches in which the type blocks are 35 mounted, and when the retaining device 24 is withdrawn the type blocks may be removed from the case by inward longitudinal movement. The heads or shoulders 18 may also pass the levers 19 and 21 when being 40 withdrawn from the case.

Each of the type bar heads 17 may be provided with one or more characters. If desired the designation of the year may be printed upon one of the type bars and any 45 desired words or abbreviations, or other identifying data may be upon the remaining type bars. The matter to be printed by the special type may be varied at will by changing the type blocks when desired.

- 50 In the specimen example illustrated in Fig. 10 one of the type blocks has printed the designation of the year, as shown as A, and abbreviations of months are printed by other type blocks in alinement with the days 55 of the months printed in the column B, and

the items or amounts printed in the column C.

In performing work of this character each line of printing including the designation of the month, the day of the month and the item or amount corresponding to that day is printed at the same operation of the printing mechanism, the type-carriers being controlled in their movements by stops set in the differential mechanism. Thus the stop 70 of the differential mechanism corresponding to the type block having thereon the designation of the year is set in the highest numerical order, and that type-carrier is then operated in the usual manner and 75 printing is effected by operation of the hammer against the type as in the ordinary operation of the machine in printing any number. Then, when it is desired to print the designation of a month and the day of 80 the month in alinement with an amount, the stop in the differential mechanism corresponding to the type block that will print the designation of the particular month in question is set in the highest numerical 85 order, and stops in the differential mechanism in next adjacent numerical orders are set for printing the numerals of the day of the month, and also the stops in the differential mechanism for printing the amount 90 are set by the operation of the keys in the usual way. After the stops have thus been set the type-carriers are operated and the word or abbreviation, the date and the amount are all printed at one operation on 95 the same line.

The Dalton and other adding machines now on the market are provided with well known mechanism for preventing the printing of ciphers between the different columns, so that no ciphers will be printed between the date column and the column containing the items or numbers. It is contemplated that my invention will be employed in such machines and the specimen 105 example illustrated in Fig. 10 is an example showing the ciphers omitted between the date column and the item column. Such machines are also equipped with means for preventing the addition of the numbers corresponding to the dates, but will permit 110 transferring or carrying over from lower orders into the adding mechanism corresponding to the date column. Since such mechanism is well known, it is unnecessary 115 to illustrate or to specifically describe the same herein.

On some occasions it may be desired to have one or more of the type blocks permanently mounted, so that they cannot be 120 removed. For instance, it may be desired to retain the levers 19 and 21 from becoming displaced when any of the type blocks are removed. To obviate that trouble one 125 of the type blocks in the series controlled 130

4
by the lever 19 and one of the type blocks in the series controlled by the lever 21 may be permanently mounted. Preferably the upper type block in the series controlled by the lever 19 and the lower type block in the series controlled by the lever 21 will be permanently mounted, so that it cannot be moved when the retaining device 24 is removed. For holding said two type blocks permanently in position and preventing dislocation thereof when the retaining device 24 is removed, two lugs 27 are formed on the type-carrier opposite the upper type block and also opposite the lower type block to prevent lateral movement of said type blocks when the retaining device 24 is removed. Thus the upper and the lower type blocks will be permanently retained from displacement, thereby holding the levers 19 and 21 in proper position, while the remaining type blocks are being interchanged.

In Figs. 8 and 9, I have illustrated a modified or alternative form of retaining device for the type blocks. This modified or alternative form of retaining device consists of a resilient loop 28 adapted to pass into the same notch in which each type block operates and having a bent or hooked end 29 adapted to engage in a hole in the type-carrier to prevent displacement thereof during operation of the type-carrier. Thus there is an individual retaining device for each type block so that any selected type block may be released and withdrawn without loosening any of the others.

It will be understood, of course, that in illustrating the specimen example in Fig. 10, I have in no sense limited the invention for use in printing any specific word or abbreviation. The essence of the invention is the provision of means or mechanism for the equipment of some of the usual type-carriers of the adding machine for printing any desired words or abbreviations. Preferably also the type-carrier in operating to print the words, abbreviations or other data, is controlled by the differential mechanism of the adding machine so that the type-carrier may also be used when desired for printing digits of numbers.

It is apparent that the form of the invention may be varied extensively without departure from the spirit and scope of the invention, and also that the use of the invention is not limited to arcuate type-carriers upon which I have chosen to illustrate it for convenience; nor is it necessary that the logotype-carrier shall be under control of the differential mechanism. Any other suitable means for controlling the logotype-carrier may be employed.

What I claim and desire to secure by Letters Patent is:—

1. In an adding and recording machine, 65 the combination with a type-carrier, a type

support carried by said type-carrier and having notches therein, and a series of relatively movable type mounted in said notches, of a removable device preventing withdrawal of said type blocks from said support and also preventing lateral movement of said type blocks relative to said type-carrier and said support. 70

2. In an adding and recording machine, the combination with a type-carrier and a support for the type secured to said type-carrier, of a series of relatively movable type supported by said support, and a removable device for preventing withdrawal of the type from said support, and also preventing lateral movement of said type relative to said support and said type-carrier. 75 80

3. In an adding and recording machine, the combination with a type-carrier and a support for the type secured to said type-carrier, of a series of type blocks mounted in said support for longitudinal movement, means limiting longitudinal movement of said type blocks in both directions, and a removable device supported by the type-carrier preventing withdrawal of said type blocks from said support and also preventing lateral movement of said type blocks relative to each other and retaining said type blocks in alignment with each other. 90 95

4. In an adding and recording machine, the combination with a type-carrier and type blocks supported by said type-carrier for longitudinal movement, of a device secured to the type-carrier for preventing lateral movement of said type blocks in one direction, and a removable device supported by the type-carrier preventing lateral movement of said type blocks in the other direction and preventing withdrawal of said type blocks from said type-carrier. 100 105

5. In an adding and recording machine, the combination of a type-carrier, a series of relatively movable type blocks supported by said type-carrier, a lever for actuating said type blocks in one direction, means for guiding said type blocks, and a removable retaining device preventing lateral movement of said type blocks. 110

6. In an adding and recording machine, 115 the combination with a type-carrier, a series of type blocks supported by said type-carrier, and shoulders limiting movement of said type blocks in both directions, of a lever pivoted on said type-carrier for holding said type blocks in idle position, a spring acting on said lever to hold said type in idle position and to restore them to idle position after being driven to print, a hammer operable to drive said type blocks to print in opposition to said lever and spring, and a removable retaining device supported by said type-carrier for holding said type in alignment. 120 125

7. In an adding and recording machine, 130

- the combination with a type-carrier, and series of separately movable type blocks supported by said type-carrier, of a lever for each of said series, means actuating said levers to move said type blocks longitudinally in one direction, and a removable retaining device holding said type blocks in engagement with said levers.
8. In an adding and recording machine, the combination of a type-carrier, a series of removable type blocks supported by said type-carrier, a lever pivoted on said type-carrier and engaging a number of said type blocks, a second lever pivoted on said type-carrier and engaging others of said type blocks, and means for actuating said levers to move said type blocks longitudinally in one direction, of a retaining device holding said type blocks in engagement with said levers.
9. In an adding and recording machine, the combination with a type-carrier, a series of type blocks supported by said type-carrier, shoulders limiting movement of said type blocks in both directions, a lever pivoted on said type-carrier for holding said type blocks in idle position, a spring acting on said lever to hold said type blocks in idle position and to restore them to idle position after being driven to print by the hammer, and a hammer operable to drive said type to print in opposition to said lever and spring, of a removable retaining device holding said type blocks in engagement with said lever, and means for preventing dislocation of said retaining device during operation of said type-carrier.
10. In an adding and recording machine, the combination with a type-carrier, a series of type blocks supported by said type-carrier, shoulders limiting movement of said type blocks in both directions, a lever pivoted on said type-carrier for holding said type blocks in idle position, and removable means supported by said type-carrier holding said type blocks in engagement with said lever and being removable to enable said type blocks to be disengaged from said lever. 40
11. In an adding and recording machine, the combination with a type-carrier, a type supporting case secured to said type-carrier, a series of type blocks operatively carried by said supporting case, a lever supported by said type-carrier for holding said type in idle position, and removable means supported by said type-carrier holding said type blocks in engagement with said lever. 50
12. In an adding and recording machine, the combination of a type-carrier, a longitudinally movable type block supported by said type-carrier, an actuator for moving said type block in one direction to its normal position after said type block has been actuated to print, means for guiding said type block, and a movable retaining device preventing lateral movement of said type block and retaining it from withdrawal from its proper position on the type-carrier. 60 65

BIRNEY DYSART.

Correction in Letters Patent No. 1,278,612.

It is hereby certified that in Letters Patent No. 1,278,612, granted September 10, 1918, upon the application of Birney Dysart, of Cincinnati, Ohio, for an improvement in "Adding and Recording Machines," an error appears in the printed specification requiring correction as follows: Page 1, line 82, for the word "of" read *or*; and that the said Letters Patent should be read with this correction therein that the same may conform to the record of the case in the Patent Office.

Signed and sealed this 8th day of October, A. D., 1918.

[SEAL.]

R. F. WHITEHEAD,

Acting Commissioner of Patents.

Cl. 197—1.
